UNITED STATES PATENT OFFICE

ANDREW BODOR, OF NEWARK, NEW JERSEY

PAPER CONTAINER

Application filed March 5, 1931. Serial No. 520,283.

This invention relates to paper containers for liquids, of a type specially designed for use as a milk receptacle, being simulative in shape to the common glass milk bottle, but embodying many features of superiority.

One of the objects of the invention is to produce a paper container far lighter in weight, less liable to fracture than a glass container and so cheap to construct that it can be thrown away after a single use.

A further feature is in the provision of a paper container in which a closure element may be hermetically sealed, positively preventing the entrance of air or water, and being equally effective in retaining its contents free from contamination or loss.

Another purpose is to produce a container capable of withstanding rough handling without yielding of its walls or causing leaks, and which is readily opened when the contents is required.

These important purposes are attained by the novel, practical and simple construction and combination of parts hereinafter described and shown in the annexed drawing, constituting a component of this disclosure, and in which:

Figure 1 is a perspective view of the container blank as partially coiled.

Figure 2 is a perspective view of the container after the cone forming operation.

Figure 3 is a side view of the container after the second operation.

Figure 4 is a fragmentary sectional view of the same, drawn to an enlarged scale.

Figure 5 is a side elevational view of a completed container.

Figure 6 is a top plan view thereof.

Figure 7 is an enlarged longitudinal sectional view of the upper part of the finished container, the view being taken on line 7-7 of Figure 6.

The upright walls of the container are made from a unitary oblong rectangular blank 10 of heavily calendered paper flat, uncreased and presenting four straight unbroken edges.

The width of the blank is such as to produce a complete container, entirely without waste, and its length is preferably such as to

be plurally coiled to constitute a cylinder 11, the end edges passing each other and being firmly and smoothly secured, both inside and outside, by an adhesive unaffected by liquids.

These cylinders, which are uniform in diameter, length and all other respects, are placed upon a mandrel, tapered for approximately half the length of the container, and there subjected to a rotating conical die which, in connection with the mandrel, produce a series of evenly spaced, uniform plaits or ruffles 12 widest at their upper extremity and gradually merging, as at 13 into the cylindrical body 14, these plaits being all turned in the same direction and produce an essentially smooth surface.

The mouth portion, that is the upper end, of the container is enlarged by specially designed machinery, which also forms a flat cap receiving seat 15 having a raised marginal flange 16 tapered slightly outward above an annular recess, which is formed by an extension or bead 17, level with the seat 15, and which is adapted to receive a plain flat circular cap 18 and retain it therein. The bottle is conveniently manipulable by this bead and is rigidified thereat by the cap 18.

The raised flange 16 is tapered outwardly to permit easy insertion of the cap, after which the flange is folded inwardly by plaiting, covering the cap and producing an effective double seal on the container, as at 19 in Figs. 5 and 6. Said seal, which is substantially dome-shaped, serves to cast off any particles or moisture which would otherwise rest or accumulate on the seat 18.

The bottom of the container is preferably formed by the insertion of a flanged disc, treated with an insoluble adhesive and further secured by forming an annular row of corrugations 20, thereafter coiling the extending lower edges of the bottom flange to produce an inset bead, as indicated at 21 in Fig. 5.

Both the inside and outside of the container are coated with melted mineral wax, thus effectually sealing the contents against the passage of air or liquids.

Due to the double or triple walls of the container an efficient, firm and conveniently

handled structure is produced, and by reason of designing special machinery for its construction, in addition to its simplicity and freedom of waste, the containers can be 5 produced at a low cost.

From the foregoing it will be seen that a simple device for this purpose has been disclosed in the preferred form of its embodiment, but it is not desired to restrict the 10 details to the exact construction shown, it being obvious that changes, not involving the exercise of invention, may be made without conflicting with the scope of the appended 15 claims.

Having thus described the invention, what is claimed as new and desired to secure by Letters Patent is:—

1. A paper container comprising a smooth cylindrical body having a plaited tapering 20 upper portion, an annular flange extending outwardly near the top to constitute a cap receiving seat, and plaited elements on said flange to completely cover a cap positioned on said seat.

2. A paper container comprising a plain cylindrical body having a tapering upper portion flanged outwardly near the top to form a flat cap receiving seat, said tapering portion being plaited and a cylindrical extension thereabove also plaited and infolded to 30 extend over a cap on said seat.

3. A paper container for liquids having a cap seat formed at the top, a cap on said seat, an annular flange on the margin of 35 said seat adapted to be bent inwardly in multi-folds to cover said cap, and sealing material uniting the cap and folds.

4. A paper container comprising a double-walled cylindrical body having a tapering 40 upper portion terminating in a mouth having a flat seat, a cap disposed on said seat, and an inwardly extending plaited cover over said cap, said cover being unitary with said body.

5. A paper container comprising a cylindrical body having a tapering upper portion flanged outwardly near the top to form a flat cap receiving seat, a series of overlying plaits formed in a cylindrical extension on 50 the margin of said seat, said plaits being bent inwardly to closely and completely cover a cap on the seat, said plaits being tightly compressed, and means for rendering said plaits and cap impervious to air and moisture.

6. In a bottle having a sheet of paper formed into a body comprising a cylindrical portion, and a neck tapering therefrom, a circumferential extended bead at the narrow end of said neck, which forms a mouth, 60 said bead providing an internal annular seat, a flat cap supported on said seat, and a portion of said sheet continuous with said bead and turned inwardly and downwardly 65 on to said cap to shield the latter.

7. A bottle comprising in combination with a sheet of paper which is formed into a body having a cylindrical portion, and a neck tapering from one end thereof and forming at its narrow end a mouth, a bottom for the 70 other end of said portion, a circumferential extended bead at said mouth, said bead providing an internal seat, a flat cap supported on said seat, and a portion of said sheet continuous with said bead and turned inwardly and downwardly on to said cap to shield the latter.

8. A bottle comprising in combination with a sheet of paper which is formed into a body having a cylindrical portion, and a 80 neck tapering from one end of said portion and forming at its narrow end a mouth, a bottom for the other end of said portion, a circumferential extended bead at said mouth, 85 said bead providing an internal seat, a flat cap supported on said seat, a portion of said sheet continuous with said bead and turned inwardly and downwardly on to said cap to shield the latter, said bead providing manipulating means for the bottle, and means 90 for rigidifying said mouth comprising said cap during the manipulating operation.

In testimony whereof I affix my signature.
ANDREW BODOR.
